UNITED STATES PATENT OFFICE.

WILLIAM C. MARTINEAU AND CLARENCE R. MARTINEAU, OF ALBANY, NEW YORK.

DEVICE FOR TREATING STRIPS OF CARD OR PAPER.

1,170,655.

Specification of Letters Patent.

Patented Feb. 8, 1916.

Application filed August 13, 1914. Serial No. 856,647.

To all whom it may concern:

Be it known that we, WILLIAM C. MARTINEAU and CLARENCE R. MARTINEAU, both citizens of the United States, and residents 5 of Albany, Albany county, New York, have invented certain new and useful Improvements in Devices for Treating Strips of Card or Paper, of which the following is the specification.

10 Our invention relates to a mechanism or device for treating strips of card board or paper whereby a plurality of such strips may be embossed, printed upon, stapled together or otherwise manipulated, and afterwards 15 cut or torn into cards, tags or the like, each of which may have a distinctive word or character imprinted or written thereon.

15 The object of our invention is to produce a cheap, simple, durable and efficient means to these ends.

Further objects of the invention will appear in this specification and be pointed out in the claims.

25 In the drawings, Figure 1 is a side elevation of our device, the outer casing being removed; Fig. 2 is a front elevation of the same; Fig. 3 is a top plan view; Figs. 4 and 5 are partly sectional views of minor details.

30 11 designates the outer wall of the machine, provided as shown with a partial central partition 12, the sides of the casing and the central wall being formed with U-shaped sockets 13. In these sockets are placed the ends of ball bearing rolls 14. Any desired number of these sockets and rolls may be employed, 3 being shown in the drawings. In the particular example 35 of our invention here illustrated the forward roll 14 carries a roll of cardboard 15, while the two rear rolls each carry strips of paper 16. These strips superposed one upon the other are carried forward through 40 slots 17 and 18 in a front longitudinal box portion 19. Forward of the rolls is a shaft 20 in which is cut a key-way 21. Mounted on the shaft 20, and keyed for longitudinal movement only thereon is a friction wheel 45 22, see Fig. 4, which bears on the top of strips 15, 16. Immediately below roll 22 and beneath strips 15, 16, is a small friction roll 23 mounted in the end of a fork lever 24, which is supported on a pedestal 25, the 50 roll 23 being held firmly against the strips by a coiled spring 26. A button 26^a mount-

ed on a pedestal 26^b may be used to lower roll 23 against the action of spring 26. It will be noted that this last named device is duplicated on each side of partition 12. 60 Also mounted on shaft 20 is a hammer 27 having a lower face 28 and an integral rear post 29, the whole being mounted for limited longitudinal and rotary movement on the shaft, see Fig. 5. Also mounted on shaft 20 adjacent roll 22 and keyed to the shaft in like manner is a ratchet wheel 30 with which engages a spring pawl 31 fitted on post 29. Face 28 of hammer 27 is adapted to strike on a bed plate 32 through openings 33 in the top 34 of front box 19. It is normally raised therefrom by a coil spring 44, the supporting eye 45 of which is adapted to longitudinal movement on a shaft 35 near the top of wall 11. 75

Mounted in box 19 are two rollers 36 over which runs an endless band or bands of carbon ribbon or paper. In the present case a single double-faced carbon band is used which runs transversely between paper strips 16. At one end of box 19, see Figs. 1 and 3, is a friction roll 36^a bearing against the carbon band and mounted on a shaft 37, which passes through the rear wall of box 19, and carries a bevel gear 38, 80 meshing with a second bevel gear 39, mounted on a suitably supported short shaft 40, which carries a sprocket wheel 41 connected by chain 42 to a sprocket 43 on shaft 20. 85

90 The operation of our device will be readily understood from an inspection of the drawings. The various parts are assembled as shown and the cardboard strip 15 and paper strip 16 mounted on their respective rolls 14, are passed through slots 17 and 18 and box 19, see Fig. 1. Each of the strips may be previously printed to form an uncut series of cards, tags or the like, the length of which will be the width of the strips, see Fig. 3, and the height of which will be determined by the width of box 19. The face of the top strip 15 is exposed through opening 33 in plate 34, so that characters or words may be manually 100 written or stamped on the face of strip 15, and by means of the carbon sheet or band, be duplicated on strips 16. The face 28 of hammer 27 may be formed as desired for the purpose for which it is intended, e. g., 105 it may be artificially roughened to prevent alteration of the characters written or 110

printed on sheet 15; it may be provided with a marking surface and a ribbon, as in the case of the ordinary dating stamp; or with a staple holding device, or die for 5 punching holes, or the like. None of these means is shown in the drawings, as they are all well known in various arts and form no part of this invention.

When hammer 27 is released post 29 integral therewith is drawn to its vertical position, see Fig. 1, by spring 44, and the engagement of pawl 31 with the teeth of ratchet wheel 30, serves to partially rotate shaft 20, whereby pressure rolls 22 and 23 10 act to force forward strips 15, 16, so that they project through slot 18, see Fig. 1. If desired, the projecting card or tag thus written or imprinted in part as just described; may be torn off, while strips 16 15 may remain as a continuous duplicate record of the cards. Of course, all three strips may be torn off as desired.

Where characters have been manually produced on strips 15 and 16, it is obvious 20 that a movement of hammer 27, even if it has in this case no other function, will be necessary to feed the strips forward, as just described. Where a single, double-faced carbon band is used, as shown in the drawings, it will of course be necessary or 25 convenient that the upper strip 16 be sufficiently translucent that the characters thereon may be read therethrough. This device is common in so many arts that further description seems unnecessary.

When the operator finds that the rolls 15 and 16 are nearly exhausted, similar rolls may be mounted in the sockets 13 at the 30 other side of the duplicate box, and carried forward through slots 17 and 18 as before. The hammer, friction roll 22, ratchet wheel 30 and their connected parts may be moved longitudinally on shafts 20 and 35, and the 35 operation of producing printed, embossed, or otherwise treated strips of cardboard or paper may be continued as already described. It will of course be understood that this operation of equipping one side of the device with the strips of cardboard 40 or paper may be done at any time in the intervals of business. It will be also understood that many mechanical alterations may be made in the device, without departing from the spirit of our invention.

55 What we claim is:

1. A device for treating strips of paper or card, including duplicate means each constructed and fitted to independently support a plurality of strips so that they may be 60 passed in superposition over a support; means for moving a carbon strip transversely of the paper strips; a hammer for acting upon a portion of the upper paper strip; means for automatically moving each of 65 such pluralities of strips forward; and

means for moving said hammer and said strip moving means transversely of the strips.

2. In a device for treating strips of paper or card, a casing; means within said casing 70 for supporting a plurality of strips; means for guiding such strips in superposition out of said casing; a hammer for impressing such strips; a friction roll in contact with one face of such plurality of strips and directly connected for operation by the return movement of said hammer; a second roll co-operative with said friction roll and normally bearing the opposite face of such plurality of strips; a spring actuated lever 80 on which said second roll is mounted; and a pivoted button adapted to be forced against said lever for continuously holding said second roll out of operative position.

3. In a device for treating strips of paper or card, a casing; duplicate means side-by-side within said casing for supporting a plurality of strips; duplicate means for guiding such strips in superposition out of said casing; a shaft forward of said strip 90 supporting means; a hammer and strip feeding means mounted on said shaft for movement longitudinally thereof whereby they may be placed in operative relation with either of said strip supporting means.

4. A device for treating strips of paper or the like, including a casing; duplicate, side-by-side means in said casing, each of which means is adapted to independently support a plurality of independent, separately removable, strip carrying rolls, each of said rolls being adapted to carry a strip of paper so that such strips may be passed in superposition over a support; and a single hammer adapted to be moved in a plane parallel to those of said rolls, and thereby adapted to operate on paper strips supported on either of said pluralities of rolls.

5. A device for treating strips of paper or the like, including a casing; duplicate, side-by-side means in said casing, each of which means is adapted to independently support a plurality of independent, separately removable, strip carrying rolls, each of said rolls being adapted to carry a strip of paper so that such strips may be passed in superposition over a support; means for automatically moving a unitary carbon strip transversely of such paper strips carried on either of said pluralities of rolls; and a single hammer adapted to be moved in a plane parallel to those of said rolls, and thereby adapted to operate on paper strips supported on either of said pluralities of rolls.

6. In a device of the class described, a casing having parallel side walls and a central partition of less length than said walls and positioned therebetween; independent means on each side of said partition for supporting a plurality of strip-carrying rolls;

a transverse shaft in said casing in front of said partition; a single hammer and sheet feeding means mounted for longitudinal movement on said shaft whereby they may 5 be operated in coöperation with said rolls on either side of said partition.

7. In a device of the class described, a casing having parallel side walls and a central partition of less length than said walls 10 and positioned therebetween; independent means on each side of said partition for supporting a plurality of strip-carrying rolls; a transverse rotary shaft in said cas-

ing and forward of said partition; a single hammer and sheet feeding means mounted 15 for longitudinal movement on said shaft whereby they may be operated in coöperation with said rolls on either side of said partition; and unitary carbon strip feeding means operative by said shaft in either position of said hammer.
